(57) **CLAIM**

The ornamental design for a roof-top tent for vehicle as shown and described.

DESCRIPTION

FIG. 1 is a front elevational view of a roof-top tent for vehicle showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is a first perspective view of the roof-top tent for vehicle showing the new design in a folded state;

FIG. 10 is a second perspective view of the roof-top tent for vehicle showing the new design in the folded state;

FIG. 11 is an enlarged view of the encircled portion '11' in FIG. 1 thereof;

FIG. 12 is an enlarged view of the encircled portion '12' in FIG. 7 thereof;

FIG. 13 is an enlarged view of the encircled portion '13' in FIG. 7 thereof;

FIG. 14 is an enlarged view of the encircled portion '14' in FIG. 8 thereof; and,

FIG. 15 is an enlarged view of the encircled portion '15' in FIG. 8 thereof.

The long-short-short-long dashed broken lines shown in FIGS. 1, 7, 8, and 11-15 depict the limits of the enlarged views and form no part of the claimed design. The short dashed broken lines shown in FIGS. 1-15 are for the purpose of illustrating portions of the article that form no part of the claimed design.

1 Claim, 15 Drawing Sheets
